UNITED STATES PATENT OFFICE

PERCY Q. WILLIAMS, OF TOLEDO, OHIO

LEER FEEDER

Application filed July 28, 1928. Serial No. 295,966.

The present invention relates to improvements in leer feeding mechanism and particularly to that type of feeder forming the subject matter to my Patent 1,537,277 dated 5 May 12, 1925.

In leer feeders of the above character, and as disclosed in the present application, bottles or similar articles are placed upon an endless belt conveyor at regular time intervals and carried in a cumbent position to one end of said conveyor. At this end of the conveyor a holder or pocket is provided to receive said articles as they leave the conveyor one at a time and are placed in an upright position upon a leer conveyor which forms the bottom of said pocket. A pair of co-operating jaws form the outer end wall of the pocket and are periodically opened in timed relation to projection of a ware 10 pusher bar into said pocket, so that articles may be removed from the pocket by the way of an opening formed between and by separation of the jaws.

From time to time bottles or the like articles fall over and become lodged between the jaws of said holder preventing the latter from closing and consequently precluding normal operation of the mechanism. This would ordinarily result in an accumulation 20 of articles in the holder and serious injury to, or perhaps breaking of certain of the articles.

An object of the present invention is to provide means operating automatically to quickly remove bottles from between the jaws so that normal operation of the feeder may be resumed with the least interruption. To this end the invention consists in the provision of auxiliary means which operates automatically, in the event the above condition arises, to cause a continued operation of the bottle pusher and repeated opening and closing movements of the jaws of the holder. Such operation of the pusher and jaws is continued until the holder jaws are cleared of the interfering bottle or other article and normal functioning of the feeder is resumed.

Other objects will be apparent hereinafter. In the drawings:

50 Fig. 1 is a fragmentary plan view.

Fig. 2 is a fragmentary side elevation.

Fig. 3 is a cross sectional view taken substantially along line III—III of Fig. 2.

Fig. 4 is a detail plan view showing a portion of the main circuit closer.

Fig. 5 is a fragmentary plan view similar to Fig. 1, and showing the bottle holding jaws open.

Fig. 6 is a horizontal sectional view taken substantially along the line VI—VI of Fig. 2 showing a part of the mechanism for operating the pusher and bottle holder.

Fig. 7 is a sectional view taken substantially at the line VII—VII of Fig. 6.

Fig. 8 is a detail elevation of the auxiliary circuit closer.

Fig. 9 is a detail perspective view showing the operating connections between the auxiliary circuit closer and the jaws of the bottle holder.

Fig. 10 is a detail side elevation of the main circuit closer and the electrical circuits.

Fig. 11 is a diagrammatic illustration of the main and auxiliary circuits and switches therefor.

Fig. 12 is a sectional elevation in detail showing the means for adjusting a part of the circuit closing mechanism.

The feeding mechanism constituting the subject matter of the present application is adapted to be placed between a machine for forming hollow glassware, and an annealing leer, and is operated in a fashion to arrange the ware, such as bottles, in an upright position in rows extending across the usual leer conveyor which carries the ware thru the leer tunnel for tempering. This feeding mechanism includes an endless conveyor whose ware delivering end reciprocates transversely over the ware receiving end of the leer conveyor and places articles in an upright position on the latter at regular intervals.

The feeder comprises an elongated main frame 15 having vertical side members 16 spaced apart and arranged in parallel relation, and supporting therebetween a sprocket 17, or the like, over which an endless belt conveyor 18 is trained. This construction may well be identical to that illustrated in my Patent 1,537,277 above referred to. Also,

this frame 15 together with the belt conveyor is adapted to oscillate in a horizontal plane and thereby move the delivery end "D" back and forth over and transversely of the ware receiving end of the leer conveyor 19 (Fig. 2).

At the delivery end "D" of the feeder, the side members 16 extend a short distance beyond the belt conveyor 18 and in conjunction with the leer conveyor 19 and a gate comprising a pair of separable jaws 20, form a bottle holder or pocket 21 into which the bottles or similar articles are deposited for momentary retention just prior to being moved to their final positions upon the leer conveyor 19.

Each jaw 20 of the bottle holder (Figs. 1 and 9) may comprise a vertically elongated flat plate secured at its upper end to a supporting rod 23, the latter extending rearwardly over lateral wings 24 on the side members 16 of the main frame 15, and mounted in sleeves 25 which are fulcrumed upon vertical hinge pins 26, said pins being suitably fixed to and rising from the wings 24. The supporting rods 23 (Fig. 2) are adjustable lengthwise in said sleeves 25 so that the spaced relation between the jaws 20 and the delivering end of the belt conveyor 18 may be varied to accommodate different sized ware, or for other reasons. An arm 27 extends laterally outward from the sleeve 25 over each of said wings, and at its outer end is suitably connected to a push rod 28 extending rearwardly thru an opening in the upper end of operating lever 29. Coil springs 30 encircle the rod 28 at opposite sides of the lever 29 and are held in contact with the latter by washers 31, or the like. Nuts 32 (Fig. 1) are adjustable on the rods 28 to change the tension of said springs. These springs function as cushioning devices to prevent excessive pressure upon and injury to articles which may become lodged between the jaws 20.

The jaw operating levers 29 (Figs. 1, 2 and 3) extend downwardly at opposite sides of the main frame 15 and are connected to, or may form a part of, a rock shaft 33 extending transversely of and below the belt conveyor 18 and journaled in bearings 34 on the lower side of said frame 15. This shaft 33 is rocked at regular time intervals to move the jaws 20 apart to permit removal of one article at a time from the holder 21 under influence of a pusher bar 57.

It is apparent that rocking of the shaft 33 imparts a swinging movement to the levers 29 which operate thru the rods 28 and 23 to move the jaws 20 toward and from each other in alternation.

The mechanism for rocking the shaft 33 includes an arm 35 depending from the rock shaft 33 and carrying at its lower end a cam roll 36 which rides upon a circular rotary

cam 37. This cam 37 is formed on one side of a cam disk 38 (Fig. 6), which is mounted upon a constantly rotating shaft 39 extending in the direction of the length of the belt conveyor 18, and journaled in a bearing 40 formed at the lower end of a hanger, or bracket 41, the latter being bolted, or otherwise secured to the side members 16 of the main frame 15.

The cam disk 38 (Fig. 6) is driven by said shaft 39 thru a friction disk clutch 42. A bevel gear 43 (Figs. 3 and 6) is secured to the shaft 39 and runs in mesh with a bevel gear 44, the latter carried by a shaft 45 journaled in a bearing 46 and driven by the driving means (not shown) for the belt conveyor thru a sprocket chain 47. This chain 47 is trained over a sprocket wheel 48 secured to one end of the last named shaft 45 and a sprocket wheel 49 spaced upwardly from said sprocket 48 and driven by a shaft 50. This shaft 50 is journaled in bearings in the main frame 15 and mounts a sprocket 50^a which has driving engagement with the sprocket chains 18^a on the belt conveyor 18.

At regular time intervals the cam 37 is held against rotation with the shaft 39 in a fashion and for a purpose to be described hereinafter. Accordingly, the friction disk clutch 42 (Fig. 6) is constructed to allow this cam 37 to remain stationary during predetermined intervals while the driving shaft 39 continues its rotary movement. This construction includes a sleeve 51 keyed to the shaft 39 and enclosing a sleeve 52 extending axially from the disk 38. One of the clutch disks is carried by the external sleeve 51 while the other disk is carried by the cam disk 38 (Fig. 6). A thrust bearing 55 is interposed between said disk 38 and a bearing 40 for obvious reasons. These disks are frictionally interengaged and provide driving connection between the shaft and cams. A coil spring 53 (Fig. 6) encircles one end of the driving shaft 39, and is confined between the bevel gear 43 and an adjustable collar 54. By adjusting the collar 54 lengthwise upon the shaft 39, the tension of the spring 53 may be varied to thereby control the effectiveness of said clutch 42.

A pusher cam 56 (Figs. 2 and 6) is formed on the cam disk 38 and rotates therewith at regular time intervals to actuate the bottle pusher 57 which removes the bottles or other articles from the holder or pocket for positioning upon the leer conveyor 19. This pusher 57 (Figs. 2 and 3) comprises an elongated bar extending lengthwise of and below the belt conveyor 18. This bar 57 (Fig. 3) is suitably supported in guideways 58 on said frame 15 and is normally yieldingly held in its innermost position by a coil spring 59 which connects said bar to a cross member 60, the latter forming a part of the main frame 15.

A cam roll 61 is mounted on the lower side of said pusher bar 57 and is at all times engaged with the rotary cam 56, such engagement being effected by the coil spring 59. 5 Normally, the outer end of the pusher bar 57 occupies a position outside of the pocket 21 (Fig. 2) into which bottles or similar articles are delivered by the belt conveyor 18. During the intervals between projection of the pusher bar 57 into the said pocket 21, bottles are delivered to the pocket and set upright therein upon the leer conveyor 19 as will be apparent hereinafter.

For the purpose of periodically interrupting reciprocation of the pusher bar 57 so the latter is held without the pocket for predetermined periods of time to allow free entrance of bottles or the like into said pocket, rotation of the cam 56 (Figs. 2, 3, 6 and 7) is discontinued at regular time intervals. This is obtained by periodic projection of the stop finger 65 into the path of travel of the lug 66 of the rotary cam 37. This stop finger 65 is supported on a frame 67 (Figs. 2 and 7) which is fulcrumed upon a horizontal hinge pin 68. This hinge pin 68 extends thru a sleeve 69 formed on the bracket 41 and has its end portions projected into collars 70 formed at the upper end of said frame 67. Thus, the frame and stop finger 65 are free to swing about said hinge pin and thereby cause periodic engagement between said finger 65 and lug 66. The stop finger 65 (Fig. 7) is yieldingly connected to the frame 67 by slidingly mounting the former upon a vertical pin 71 and arranging a coil spring 72 upon said pin in a fashion to exert upward pressure on the finger and yieldingly hold the latter in engagement with the lower face of said frame 67. A retaining nut 73 is threaded upon the lower end of said pin 71 and is adjustable to vary the tension of the spring 72.

This construction materially decreases the probability of breaking the stop finger 65 or lug 66 when the finger is projected into the path of said lug 66 to stop rotation of the cams 37 and 56. A coil spring 75 (Fig. 3) connects the lower end of the frame 67 to a portion of the main frame 15 and operates to yieldingly normally hold the stop finger 65 in the path of travel of said lug 66. The tensioning member 79 may be adjusted to regulate the effectiveness of the coil spring 75.

The frame 67 is intended to be swung outwardly at regular time intervals and in timed relation to movement of the jaws 20 of the holder away from each other for the purpose above stated, by a solenoid 76 (Figs. 2, 3 and 6) co-operating with an armature 77 carried by said frame 67. This solenoid is mounted on an arm 78 forming a part of said bracket, or hanger, 41. The solenoid 76 is energized at regular intervals by means which is actuated by the delivery of a bot-

tle into the holder 21. Each time a bottle is deposited in the holder or pocket 21, a mechanism to be described is actuated to operate a circuit closer in the circuit including said solenoid 76, whereby the latter is energized and pulls the armature in a direction to swing the frame 67 outwardly to remove the stop finger 65 from the path of travel of the lug 66. The cams 37 and 56 may then rotate and thru the rods and rock arm move the jaws 20 apart and simultaneously project the bottle pusher 57 into the pocket 21 to remove an article from the latter to its final position upon the leer conveyor 19.

The circuit closer and control mechanism therefore will be now set forth.

The main circuit closer (Figs. 9, 10 and 11) is mounted upon a base block 80 arranged on the upper side of the main frame 15 and includes a pair of horizontally disposed upper and lower pins or rods 81 and 81^a respectively, the former being constructed of suitable current conducting material so that it may constitute a portion of the electrical circuits, as will be apparent hereinafter. Preferably, these pins or rods 81 are arranged within sleeves 82 of insulating material. The upper pin 81 (Figs. 10 and 11) is formed with a contact 83 at one end adapted to cooperate with a contact 84 on the switch arm 85, the latter being fulcrumed upon the lower pin 81^a.

A conductor 86 (Figs. 10 and 11) forms one side of an electrical circuit including the solenoid 76 and a battery 87 or the like source of electrical energy. The other side of this electrical circuit includes a conductor 88 leading from the solenoid 76 to the contact 84 on the upper pin 81.

A current conductor 89 connects the contact 83 on one end of the upper pin 81 to the battery 87. Thus, it is seen that with engagement between the contacts 83 and 84 the electrical circuit thru the solenoid 76 is closed to thereby energize the latter and cause the armature carrying frame 67 to swing toward said solenoid and remove the stop finger 65 from the path of travel of the lug 66. The cam disk 38 may now rotate to effect opening of the jaws 20 and reciprocation of the pusher bar 57 as previously stated.

The switch arm 85 is normally yieldingly held in a position to separate the contacts 83 and 84 to thereby allow the coil spring 75 (Fig. 3) to hold the armature carrying frame 67 in its innermost position, wherein it positions the stop finger 65 in the path of and for engagement with the lug 66. A leaf spring 90 exerts an upward pressure upon the switch arm 85, tending to bring the contacts 83 and 84 together. A switch control arm 91 is disposed above the switch arm 85 and carries an adjustable screw 92 which normally engages said switch arm 85 and positions the latter to open the circuit which in-

cludes said solenoid 76. This control arm 91 is adapted to oscillate about a horizontal axis 93 (Figs. 9 and 10), such movement resulting from bottles or the like articles striking a trigger 94 which extends into the bottle holder 21. This trigger is connected to the control arm 91 thru a horizontally disposed bar 95 supported in suitable bearings 96 on the upper side of the frame 15. This 10 bar 95 is preferably rectangular in cross-section and has one corner resting in V-notches 97 in said bearings. Thus, the trigger is quite sensitive and quickly actuates the control arm 91 when a bottle or the like 15 strikes the trigger. The control arm 91 (Figs. 9 and 10) may carry a counterweight 98 which is adjustable lengthwise of said arm and operates to insure return of said arm to its lowermost position, in which it moves the 20 switch arm 85 downward to break the electrical circuit.

A constantly energized solenoid 99 (Figs. 9 and 10) is arranged beneath the control arm 91 to hold said arm against vibration 25 when said arm returns to its lowermost position as shown in Fig. 10. It is evident that without some means such as the solenoid 99 to prevent rebound of the control arm 91, the circuit including said solenoid 76 would in 30 all probability be closed at quite irregular time intervals if not continuously. Under such circumstances, proper operation of the feeder could not be obtained. The solenoid 99 (Fig. 10) is constantly energized by low 35 voltage current flowing thru the conductors 100 and suitable resistance 101 from the battery 87 or other source of electrical energy.

To prevent arcing between the contacts 83 and 84 (Fig. 10) a fixed condenser 102 is 40 arranged in one side of the circuit including the solenoid 76, by means of conductors 103 which connect opposite sides of the condenser to the contacts 83 and 84. This condenser absorbs current which would otherwise cause 45 arcing between said contacts.

Variation in the angular relation between the trigger 94 and the walls of the pocket or 50 holder 21 may be essential at times to obtain most satisfactory operation of the mechanism. This may be found quite desirable when the type of bottle being handled is 55 changed. Obviously, small bottles may require setting the lower end of the trigger quite close to the center of the pocket to insure engagement between the bottles and trigger. Accordingly, the core 99^a of the solenoid 99 (Figs. 10 and 12) is adjustable 60 to raise or lower the normal position of the control arm 91 and correspondingly change the angle of the trigger 94. A lock nut 98^a is used to maintain such adjustment of the core 99^a. Obviously, the set screw 92 on the arm 91 must be adjusted in accordance with the change in position of the core 99^a to insure 65 proper operation of the switch arm 85.

Each time a bottle or similar article is deposited in the holder 21 (Figs. 1, 2, 9 and 10) the trigger 94 is engaged by the article and caused to move to one side. This movement of the trigger rocks the bar 95 and thereby 70 raises the control arm 91 (Fig. 10) sufficiently to allow the switch arm 85 to move upwardly under influence of the spring 90 and bring the contacts 83 and 84 together. Thus, the circuit including the solenoid 76 is closed and the stop finger 65 is withdrawn from contact with the lug 66 on the cam 37. Thru the clutch 42 rotary movement is now imparted to the cams 37 and 56 by the constantly rotating shaft 39, resulting in separation of the jaws 20 of the bottle holder substantially as 75 shown in Fig. 5, and projection of the pusher bar 57 in the pocket or holder 21. Thus pusher bar engages the lower portion of the bottle or other article, which is standing upright 80 on the leer conveyor 19, and moves said article out of the holder by way of the opening formed between and by separation of the two jaws 20. Immediately upon movement of an article to a position beyond the trigger 94, 85 the counterweight 98 and the constantly energized solenoid 99 operate to return the control arm to full line position shown in Fig. 10. Thus, the contacts 83 and 84 are again separated to break the circuit and allow the coil 90 spring 75 to return the armature carrying frame 67 to a position in which the stop finger 65 again engages the lug 66 and stops rotation of the cams 37 and 56. It is understood that the cam 37 rocks the levers 29 to 95 open the jaws 20 of the holder and that the jaws are closed by coil springs 29^a (Fig. 2). The cam 56 engages the cam roll 61 (Fig. 2) and moves the latter together with the pusher bar 57 in the direction of travel of the leer 100 conveyor 19 to remove articles from the pocket or holder while said jaws are open. 105

From time to time bottles or the like articles fall over on their sides in the pocket 21 between the jaws, for various reasons. Generally the bottle in falling over is positioned 110 out of contact with the trigger 94 so that the electric circuit thru the solenoid 76 is broken and the cams 37 and 56 discontinue their rotary movement. Under these conditions the cams would not ordinarily resume rotation, nor would the pusher bar 57 again operate, until another bottle entered the holder and engaged the trigger 94. This might result in several bottles piling up in the pocket 115 or holder 21.

Provision is made herein to quickly clear the pocket of bottles which have fallen over between the jaws 20. An auxiliary circuit 120 closer is placed in the circuit including said solenoid 76 and operates thru said solenoid to prevent de-energization of the solenoid so long as a bottle or the like article occupies an abnormal position between the jaws 20. 125

Thus the jaws are held open and the pusher bar 57 continues to operate to remove the article from between the jaws.

This auxiliary circuit closer includes a switch arm 85^a (Figs. 4, 9 and 11) mounted on the lower pins 81^a and having an insulated contact 84^a connected thru a conductor 105 to one side of the solenoid 76. The other, or upper pin 81, carries a contact 83^a, and forms a portion of the circuit for this auxiliary circuit closer, and is connected thru the conductor 89 to the batteries 87. The other side of the circuit of this auxiliary circuit closer is formed by the conductor 86 which also constitutes one side of the other or main circuit.

A control arm 106 (Fig. 9) is arranged above the switch 85^a of said auxiliary circuit closer and mounts an adjustable set screw 107 which normally engages the switch arm 85^a and holds the latter in its lowermost position to separate the contacts 83^a and 84^a. This control arm 106 is secured to a rock shaft 108 (Fig. 9) one end of which is journaled in a bearing in the base block 80, while its other end is mounted in a bearing 109. A coil spring 110 (Figs. 5 and 9) encircles a portion of said rock shaft 108 and is arranged to exert a tension on the rod which tends to lift the control arm 106 and thereby allow the switch arm 85^a to move upwardly under the influence of the leaf spring 90^a and close the auxiliary circuit. The end of rock shaft 108 (Fig. 9) opposite that end carrying the control arm 106 is bent upwardly to form a finger 111 which at all times engages an extension 112 on one of the sleeves 25 in which the jaw carrying arms 23 are fixed.

So long as the mechanism is operating normally and bottles are being removed from the pocket 21 at regular intervals the jaws 20 open and close alternately and the pusher bar operates at regular periods. Thus the two switch arms 85 and 85^a are free to open and close periodically and thereby regulate rotation of the cams 37 and 56 and consequently control operation of the pusher bar 57 and the jaws 20 of the bottle holder.

If, however, an article becomes lodged between the jaws 20, the latter cannot resume a closed position, and accordingly the extension 112 will be moved inwardly and allow the spring 110 to yieldingly hold the rock shaft 108 in a position to lift the control arm 106 and allow the switch arm 85^a to move upwardly bringing the contacts 83^a and 84^a together. Under these conditions the cams 37 and 56 rotate continuously, thereby causing continuous reciprocation of the pusher bar 57 and movement of the jaws 20 away from each other to clear the holder of the bottle which has become positioned between said jaws. With repeated outward movement of the jaws 20 and continuation of projection of the pusher bar 57 in the pocket or holder 21, it is evident that the bottle 22 or other

article will be quickly removed from its abnormal position, and the feeding mechanism may quickly resume normal operation.

Modifications may be resorted to within the spirit and scope of the appended claims.

What I claim is:

1. The combination of a leer conveyor, pivoted cooperating jaws forming with the conveyor an article receiving pocket, means to place articles in the pocket at regular intervals, a pusher bar for removing articles from said pocket, rotary cams, connections between said cams, jaws and bar, whereby rotation of the cams periodically opens the jaws and actuates said pusher bar, means to impart a rotary movement to said cams, mechanism actuated by entry of articles into said pocket to control the periods of rotation of the cams, said last named means including a trigger projecting into the pocket in the path followed by articles entering the latter, whereby said trigger will be moved by contact with the articles, electrical devices controlled by movement of said trigger for regulating the periods of rotation of said cams, and auxiliary control means actuated by opening of the jaws to cause continued rotation of the cams and actuation of said bar while the jaws are open.

2. The combination of a leer conveyor, pivoted jaws above and forming with the conveyor an article receiving pocket, a reciprocable pusher bar for removing articles from the pocket, rotary cams, means operated by rotation of the cams to separate the jaws and project the pusher bar into said pocket, and automatic means to cause continuous reciprocation of said pusher bar while the jaws remain separated.

3. The combination of a leer conveyor, pivoted jaws above and forming with the conveyor an article receiving pocket, a reciprocable pusher bar for removing articles from the pocket, rotary cams, means operated by rotation of the cams to separate the jaws and project the pusher bar into said pocket, means operating during predetermined periods of time to hold said cams against rotation, electrically controlled mechanism operating at regular intervals to release the cams for rotation, and means whereby the pusher bar is repeatedly reciprocated during any abnormally long period of separation of said jaws.

4. The combination of a leer conveyor, means to deposit articles one at a time in an upright position on the leer conveyor, a pair of pivoted jaws, said conveyor and jaws together forming an article receiving pocket, means actuated by setting up an article in the pocket to open said jaws, a pusher for removing articles from said pocket, and mechanism operating so long as the jaws are open to actuate said pusher.

5. The combination of a leer conveyor, a frame, an endless belt conveyor thereon, means to continuously move the belt to eject

articles from one end of the belt in an upright position, a pair of pivoted jaws, said jaws and leer conveyor together forming an article receiving pocket at one end of the belt, means to open the jaws at regular time intervals to provide an opening through which the articles may leave said pocket, a mechanical pusher for removing articles from the pocket by way of said opening, and means actuated by opening of the jaws to repeatedly operate the pusher so long as the jaws are open.

6. In combination, a pair of pivoted cooperating jaws, a leer conveyor beneath and cooperating with the jaws to form a pocket, means for placing articles in said pocket periodically, means for separating said jaws at regular time intervals, a pusher bar for removing articles from said pocket by way of the opening formed between and by separation of the jaws, means to impart article propelling movement to the pusher bar, and means brought into operation by separation of the jaws to cause continuation of movement of said bar while the jaws are separated.

7. The combination of a pair of pivoted cooperating jaws, a leer conveyor cooperating with the jaws to form a pocket and constituting a bottom for the pocket, means for placing articles in said pocket periodically, means for separating said jaws at regular time intervals, a pusher bar for removing articles from said pocket by way of the opening formed between and by separation of the jaws, means to operate the pusher bar, switch operating means engaged by articles entering said pocket to control the means for separating the jaws and operating the pusher bar, and an auxiliary switch operating means actuated by separation of the jaws to cause repeated operation of the pusher bar while the jaws are separated.

8. The combination of a leer conveyor, pivoted jaws above and cooperating with the conveyor to form an article receiving pocket, the leer conveyor constituting a bottom for the pocket, means for placing articles upright in said pocket at regular time intervals, electrically operated mechanisms for opening the jaws and removing the articles from said pocket, means engaged by said articles as they enter the pocket to cause operation of said mechanism, and auxiliary means operatively positioned by opening of the jaws to cause continued operation of the article removing mechanism while the jaws are open.

9. The combination of a leer conveyor, means to deliver articles thereto comprising a ware conveyor, a pair of separable jaws at one end of the ware conveyor arranged to cooperate with the leer conveyor in forming an article receiving pocket, a pusher bar arranged for reciprocation across the pocket

to eject articles therefrom, mechanism for separating the jaws and actuating the pusher bar, electrical control means for causing operation of said mechanisms including primary and secondary circuit closers, means actuated by deposit of an article in the pocket to operatively position the primary circuit closer, and means operated by separation of the jaws to close the secondary circuit closer.

Signed at Toledo, Ohio, this 26th day of July, 1928.
